UNITED STATES PATENT OFFICE.

CHARLES E. HEYER, OF CHICAGO, ILLINOIS, ASSIGNOR TO ARTHUR M. AND ALSON E. BARNHART, OF SAME PLACE.

DESIGN FOR TYPE.

SPECIFICATION forming part of Design No. 18,037, dated February 7, 1888.

Application filed August 7, 1885. Serial No. 173,870. Term of patent 14 years.

To all whom it may concern:

Be it known that I, CHARLES E. HEYER, a citizen of the United States, residing in the city of Chicago, county of Cook, and State of Illinois, have invented and produced a new and original Design for a Font of Printing-Types, of which the following is a specification, reference being had to the accompanying typographical illustration, forming a part hereof.

The character of the design is a modern old-style broad-face Italic of medium weight; and it consists of capitals, figures, points, character &, and lower-case, and is different from any other old-style Italic in that the slope given the letters is less than twenty degrees, and the lower-case letters do not present the round appearance shown in old-style Italic letters. A special feature is shown in capital A. A short ceriph, slightly curved inside and out, extends toward the left above the connecting-point of the light diagonal line. Another light line inside extends diagonally from the middle of the left inclined light line downward and connects with the right-side heavy stroke near the bottom. In capital E the flag at the end of the center line is rather heavy, slopes backward, and is slightly curved each side, while the flags at the end of the top and bottom lines are curved inside, and the points of same extend beyond the horizontal lines obliquely. In capital F the same features are shown as regards the center and top lines. In capital H the cross-stroke extends diagonally from above the center of the left line to a point below the center of the right line. In capital K the lower right-side diagonal stroke is heavy, and it crosses and extends beyond the light line, the end being notched. The same feature is again shown in capital R, except the projecting end is curved.

Capitals M, N, U, V, W have short spurs on one or both sides, near the bottom part of each. Each of the lower-case letters, excepting b, c, e, g, o, s, t, v, w, have a long ceriph at the bottom, the lower side of which is straight, while the upper side is slightly curved outward from the heavy stroke. In lower-case i, j, l and the slanting strokes of b, d, h, k, m, n, p, r, u the upper side of the ceriph on the side at the top is curved. A special feature is shown in lower-case f, the part above the cross-line near the top curving backward and ending with a swell. In lower-case g the lower part is a flourish, at the end of which is a slight swell. The center line of the flourish is shaded, and the flourish is rather compressed. In lower-case k the short heavy lower diagonal stroke crosses the light line and projects slightly beyond it.

I claim—

The design for a font of printing-type herein shown and described, the general character of which is a quite open extended Italic letter having less than twenty degrees inclination, and marked by long sharp ceriphs on most of the letters, long oblique sharply-terminating horizontal strokes or flags on E, F, L, T, and Z, projecting back beyond the line to which they pertain in a short spur, short sharp spurs on the capitals M, N, U, and W, the backward curve of the top of the lower-case f, and the oblique cross-strokes sloping down from left to right on capitals A and H, and slightly sloping ceriphs on center stroke of capitals E and F, substantially as illustrated.

CHARLES E. HEYER.
